DELIVERY MECHANISM

Filed June 15, 1928

UNITED STATES PATENT OFFICE

EDWARD F. DUDLEY, OF OAK PARK, ILLINOIS, ASSIGNOR TO THE MIEHLE PRINTING PRESS & MANUFACTURING COMPANY, OF CHICAGO, ILLINOIS, A CORPORATION OF ILLINOIS

DELIVERY MECHANISM

Application filed June 15, 1928. Serial No. 285,618.

This invention relates to delivery mechanism for printing presses or other machinery where sheets, after having been printed, or after having been subjected to any other 5 operation, are to be delivered evenly stacked.

In printing presses or other machinery for handling sheet stock, it is vital that the sheets which are to receive an impression be under perfect control while they are being 10 fed to a printing couple. It is also important that the sheets, after having received an impression, should remain under positive control so that they may be delivered onto sheet receiving means in an even 15 stack, thereby eliminating the necessity of any manual straightening out of the delivered sheets.

It is therefore the principal object of my 20 invention to provide improved sheet delivery mechanism for printing presses and the like, wherein the travel of the sheet, after having left the printing couple, will be slowed up so that the sheets will be conveyed to the 25 delivery table at a relatively low rate of speed.

Another object of the invention resides in 30 the provision of means whereby, during part of the travel of the sheets from the printing couple to the delivery table, the movement of the sheets is pneumatically controlled.

Other objects and novel features of the 35 invention will be apparent from the following description and appended claims.

One preferred form of the improved delivery 40 mechanism forming the subject of my invention is illustrated on the accompanying sheets of drawings, in which:

Figure 1 is a diagrammatic view in side 45 elevation of the general arrangement of the cooperating parts, whereby the objects of the invention are accomplished;

Figure 2 illustrates a view of the control mechanism showing the arrangement of the pneumatic means in elevation whereby the 50 sheets as they are being delivered are controlled during part of their travel to the delivery table; and

Figure 3 is a plan view of Figure 2.

While it will be readily understood that 55 the improved delivery mechanism is subject

to modifications and can be applied to any type of sheet handling machinery without departing from the principle of the invention, I have illustrated it by way of example in conjunction with a flat bed press 55 having an impression cylinder 10 mounted in any suitable manner on the machine frame 11 of the press.

The means whereby sheets 12 are conveyed to the delivery table or board 13 preferably 60 comprises a chain delivery mechanism having one or more sheet engaging grippers 14 cooperating with cylinder grippers 15, and mounted on endless chains 16, continuously driven during the operation of the press 65 at the surface speed of the impression cylinder 10 by means of sprockets 17. In order to accommodate the chain delivery grippers to any thickness of stock within given limits. I preferably mount said grippers resiliently, 70 thereby eliminating any adjustment of the grippers that might otherwise be necessary to accommodate various thicknesses of stock. The sprockets 17 are preferably in mesh with the usual cylinder gear, not illus- 75 trated.

By means of this chain delivery mechanism, the sheets, after having been transferred from the cylinder grippers, are dropped onto a series of delivery tapes 18, 80 which are actuated by the operating mechanism of the press to travel at a speed considerably slower than that of the chain delivery grippers 15, i. e. of the surface speed of the cylinder 10. 85

Figure 1 shows the cooperating parts of the delivery mechanism in a position where a sheet 12 has just been dropped onto the delivery tapes 18 whereby they are slowly advanced towards stop fingers 19 mounted 90 on the rock shaft 20. At the moment when the leading edge of the sheet 12 reaches the plate 21, the stops 22, provided on the fingers 19, extend below the surface of said plate to arrest the forward movement of the sheet 95 12. The fingers 19 are actuated in any desired manner such as by cam means operated by the driving mechanism of the press.

As illustrated in Figure 2, the plate 21 is formed with one or more air vents 23 pref- 100

erably connected by means of a tube 24 with a vacuum valve 25 communicating in any suitable manner with a vacuum pump not shown.

5. Vacuum is applied to the valve 25 so that when the leading edge of a sheet reaches plate 21 where it will cover the air vents 23, the sheet will be held against further movement until the valve 25 is operated to 10 cut off the suction through the tube 24.

Referring again to Figure 1, I have indicated means of a well-known construction for conveying the sheets from the plate 21 to the delivery table 13. Said means comprises oscillating arms 26 pivoted at 27 to swing to and fro between the position indicated in broken lines and the position indicated in full lines. The arms 26 carry at their outer ends one or more delivery grippers 28 as well as a cam roller 29, which latter is adapted to ride over the surface 30 of a cam 31. When the cam 31 is in its position shown in Figure 2, with the roller 29, positioned as indicated in broken lines, 15 the valve 25 will be closed so that air will not be withdrawn through the vents 23 and pipe 24.

This is the position of the parts at the time when a sheet is engaged for being withdrawn from the plate 21 by the delivery grippers 28. As soon as the roller 29 is moved out of engagement with the cam surface 30, the valve 25 will again be opened and the next sheet advanced to the plate 21 20 will again be held by means of the vacuum applied by the air vents 23.

The valve 25 could be opened merely by the gravity of the cam 31, but in order to assure the proper operation of the valve, a 25 compression spring 32 is preferably provided as shown in Figure 2.

It will be readily understood that at the moment the sheets are delivered onto the delivery table 13 by the grippers 28, the latter have almost come to a complete stop and consequently the sheets as they reach the stripper fingers 33, travel at an exceedingly low speed thereby avoiding any buckling of the sheets and any irregularities in the 50 pile of delivered sheets.

I claim:

1. In a delivery mechanism for printing presses and the like, the combination of a sheet carrier operative to remove a sheet 55 from a cylinder of the press at cylinder speed, oscillating delivery means, and means continually moving at a slower speed than said carrier and adapted to receive a sheet therefrom and advance it towards said delivery means.

2. In delivery mechanism for printing presses and the like, the combination of a chain delivery having means to remove a sheet from a cylinder, oscillating delivery 60 means, and a series of delivery tapes mov-

ing continually at a slower speed than said chain delivery and adapted to receive a sheet therefrom and advance it towards said delivery means.

3. In delivery mechanism for printing 70 presses and the like, the combination of a sheet carrier, means moving at a slower speed than said carrier and adapted to receive a sheet therefrom, sheet retaining means, a delivery table, and means to remove a sheet from said retaining means and deposit it onto said delivery table.

4. In delivery mechanism for printing 80 presses and the like, the combination of a sheet carrier, means moving at a slower speed than said carrier and adapted to receive a sheet therefrom and convey it to sheet retaining means, a delivery table, and means operatively associated with said retaining means to render it inoperative and to remove a sheet therefrom and deposit it onto 85 said delivery table.

5. In delivery mechanism for printing 90 presses and the like, the combination of a sheet carrier, means moving at a slower speed than said carrier and adapted to receive a sheet therefrom, pneumatic means associated therewith, whereby sheets may be retained, a delivery table, and means operatively associated with said pneumatic 95 means to render it inoperative and to remove a sheet therefrom and deposit it onto said delivery table.

6. In delivery mechanism for printing 100 presses and the like, the combination of a sheet carrier, means moving at a slower speed than said carrier and adapted to receive a sheet therefrom, pneumatic means associated therewith, whereby sheets may be retained, a delivery table, and means operatively associated with said pneumatic means to render it inoperative and to remove a sheet therefrom and deposit it onto 105 said delivery table at a speed slower than the cylinder speed of the press.

7. In delivery mechanism for printing 110 presses, the combination of a sheet conveyor, and pneumatic means associated therewith, whereby sheets are held against movement, and means for intermittently rendering said pneumatic means inoperative.

8. In delivery mechanism for printing 115 presses, the combination of a sheet conveyor, pneumatic means associated therewith whereby sheets are held against movement, means for rendering said pneumatic means inoperative, and means for withdrawing sheets therefrom.

9. In delivery mechanism for printing 120 presses, the combination of a sheet conveyor, pneumatic means associated therewith whereby sheets are held against movement, and additional means cooperating with said pneumatic means for assisting in holding 125 said sheet.

10. In delivery mechanism for printing presses, the combination of a sheet conveyor, pneumatic means associated therewith whereby sheets are held against movement, 5 additional means cooperating with said pneumatic means for assisting in holding said sheet, and means for withdrawing sheets therefrom, as said pneumatic means is rendered inoperative.

10 Signed at Chicago, Illinois, this 13th day of June, 1928.

EDWARD F. DUDLEY.
